UNITED STATES PATENT OFFICE.

JAMES T. COWLEY, OF BOSTON, MASSACHUSETTS, ASSIGNEE TO THE LAMSON COMPANY, OF NEWARK, NEW JERSEY, A CORPORATION OF NEW JERSEY.

ELEVATOR.

1,123,493.

Specification of Letters Patent.

Patented Jan. 5, 1915.

Original application filed July 17, 1905, Serial No. 269,974. Divided and this application filed July 17, 1909, Serial No. 508,176. Renewed July 11, 1912. Serial No. 708,933.

To all whom it may concern:

Be it known that I, JAMES T. COWLEY, of Boston, in the county of Suffolk and State of Massachusetts, have invented certain new and useful Improvements in Elevators, of which the following is a specification.

The present application is a division of the application for improvements in elevators, filed by me July 17, 1905, Serial Number 269,974, Patent No. 928,364, dated July 20, 1909.

This invention relates more particularly to that class of elevators which are provided with a dumping platform for discharging the load of the car.

It has for its object the provision of means that can be actuated and controlled from any one floor of the building to operate the dumping platform at any other floor.

In the accompanying drawings which illustrate a construction embodying my invention, Figure 1 is a side elevation of an elevator apparatus showing general arrangement. Fig. 2 is a plan view of the mechanism located at each floor and showing section of the elevator car. Fig. 3 is a side elevation of the parts shown in Fig. 2. Fig. 4 is a front view of the lower part of the car. Fig. 5 is an edge view of the lower part of the slide or door showing latch and controlling bar for same. Fig. 6 is a plan view of a portion of parts shown in Fig. 4. Fig. 7 is an enlarged view of motor and the cable drum. Fig. 8 is an enlarged view of a portion of Fig. 2, and Fig. 9 is a diagram showing the mechanisms at three of the stopping points and the manner in which they are connected together, the parts being in the positions they would occupy when any one had been adjusted so as to stop the car at stopping point or floor number 3.

Referring to the drawings, 1, 2, 3, and 4 represent the floors of a building through which the elevator well extends. Within the well is the car A carried by rope B, supported near the top of the building by a sheave B² on a shaft B³ journaled in a suitable hanger. In the basement of the building is a motor C that drives a drum B' around which the rope B passes and this motor is controlled by a rheostat C'. At the different floors of the building the elevator

is accessible through doors D', D², D³, and D⁴ which slide vertically in ways.

The starting of the elevator is effected through a bell crank H (Figs. 3 and 9) connected by a link K with a smaller bell crank K' connected by a link K² with a slide K³ mounted on a vertical bar L'. The bar L' which carries the slide K³ is fixed at its ends to brackets L fastened to the wall of the elevator well. This slide K³ is made with bosses through which extend two rods J¹⁰ and J¹¹ connected at their upper ends by a belt or chain J' passing over a sheave J². One of the rods J¹⁰ is fastened by set screws J¹² to the slide K³ and the other rod J¹¹ slides loosely through the bosses of said slide and at its lower end said rod J¹¹ is connected by a bell crank C⁴ and links C³ with the motor-controlling rheostat C' so that vertical movement of that rod J¹¹ starts and stops the motor C. The reason for employing the two rods J¹⁰ and J¹¹ connected by the belt or chain J' as described is so that one rod will serve to counterbalance the other, thus reducing the labor in operating the rod J¹¹ which is connected with the controller C'. It will thus be seen that by means of the bell crank H the motor C may be started, said motor being stopped automatically as described later.

In order to prevent the operation of the car A when any of the doors D', etc., are open, or in other words, in order to permit of operating the car A only when all of the doors are closed each bell crank H is controlled by a latch H' which in turn is controlled by its respective door. This latch H' is pivoted at H⁶ and a spring H² tends to hold said latch in engagement with the bell crank H but when the vertically slidable door is closed a stud H⁴ on the door engages a pin H⁵ sliding in any suitable fixture and acting through said pin H⁵ engages the arm H³ of the latch H' thereby freeing the bell crank H so that the latter may be operated to start the car A up or down.

The "off" position of the bell crank H is midway between the extremes of its movement which is the case also with the arm of the controller C' so that if the bell crank H is swung down the controller arm is swung in one direction and a motor C is started in

one direction and if the bell crank H is swung in the opposite direction the controller arm is swung in the opposite direction and the motor C is started in the opposite direction. It will be seen, however, that if the door is open the latch H' locks the bell crank H in its "off" position and the car cannot be operated.

The studs S which carry the bell cranks F and H are fixed to a wall E', E², etc., on the different floors. This wall may be part of the building within which the apparatus is located.

As will be seen from Fig. 9 all of the slides K⁸ are rigidly connected by the rod J¹⁰ that is fastened to said slides and therefore if any of the doors is open and its respective bell crank H is locked none of the other bell cranks can be operated even though their respective doors are closed and consequently in order to start the car in either direction all of the doors must be closed.

In accordance with the invention it is desired to be able to start the car from any floor and automatically stop it at any of the other landings or stopping points and in order to accomplish this the selecting and stopping devices now to be described are provided.

Mounted loosely on the same stud S with the bell crank H is a double bell crank F which has connected to it two links F⁴ and F'. The link F⁴ is connected through a bell crank F⁶ pivoted, as at L⁵ (Fig. 3), on the bar L' with an interlocking rod F⁶ which is common to all of the bell cranks F, all of said bell cranks being connected in similar manner with said rod. The other link F' is connected with a slide F⁸ mounted in transverse ways on the slide K⁸. This slide F⁸ carries an arm G' in which is journaled the roll G (Fig. 8). There is an index alongside of the bell crank F corresponding to the stopping points or floors of the building and the rolls G are so placed on their respective slides F⁸ that when the bell crank F is opposite 1 on the index then the roll G of the first floor or stopping point is in the path of a cam A⁸ carried by the car and all the other rolls G are out of the path of said cam. When a bell crank F is shifted opposite 2, 3, or 4 on the index, then the roll G of the floors 2, 3, or 4, is brought into the path of the cam A⁸ while the other rolls G will be out of the path of said cam. The doors D', etc., each carries a latch H' normally held by a spring H¹² surrounding a pin H¹³ in engagement with a slide H⁹. (Figs. 2 and 3.) This slide H⁹ is made with a notch H⁸ which serves as a passageway for the hook of the latch H' (Fig. 5) when the notch is brought into the path of said hook. The notches H⁸ of the different slides are positioned so that when the bell crank F is opposite 1 on the index, notch H⁸ of the

floor 1 is on the path of the latch H' of that floor while all the other latches H' are in locking engagement with the slides H⁹. Likewise the notches H⁸ of the floors 2, 3, and 4 free their latches H' only when the bell crank F is opposite 2, 3, or 4 on the index. That is to say, only one latch H' is freed at a time and that when the bell crank F is opposite the number on the index that corresponds to the floor of the latch that is free so that only one door of the whole series is free to be opened at one time.

The slide H⁹ is engaged by the pin H¹⁰ on the slide F⁸ and when the bell crank F is shifted to select the stopping point for car A the roll G at the stopping point selected on the index adjacent the bell crank F is brought into the path of the cam A⁸ and at the same time the pin H¹⁰ shifts the slide H⁹ at the selected stopping point so as to free the latch H' that cooperates therewith. This selection having been made the operator throws the bell crank H up or down according to the direction in which he desires the car to travel. As soon as the cam A⁸ strikes the roll G at the selected stopping point the car is automatically stopped and dumped.

The stopping is effected as follows: The cam A⁸ lifting on the roll G raises the slide K⁸, rod J, as well as all of the other slides K⁸ that are connected with said rod which results in a downward movement of the loose rod J thereby shifting the controller C' so as to stop the motor C. It will thus be seen that the car A may be started from any floor and automatically stopped at any selected one of its stopping points and that the door at that stopping point is automatically unlocked.

The bottom A' of the car A is pivoted at A² (Figs. 2, 3, 4 and 6) and this pivoted bottom is normally supported by two latches A³ pivoted thereto and engaging at their lower ends two brackets A⁴ secured to the sides of the car. Through these brackets A⁴ slides the bar A⁵ with notches A⁹, A¹⁰ in its opposite ends. The bar A⁵ carries the cam A⁸, said bar being normally held with cam A⁸ projected so as to engage with the rolls G by a spring A⁶. When during the travel of the car the cam A⁸ strikes the roll G at the selected stopping point the bar A⁵ is slid in the direction indicated by the arrow in Fig. 4 far enough to bring the notches A⁹ and A¹⁰ below the lower ends of the latches A³ and A⁴. The latter being then unsupported the bottom A' tilts and the contents of the car is discharged onto a trough or the like S' at the selected stopping point.

The cam A⁸ as shown in Fig. 4 is made with two inclines one extending up and the other down from a pocket which separates the two inclines so that during the travel of the car in either direction the incline which

engages the roll G first acts to shift the bar A⁵ so as to free the bottom A' and then when the roll G enters the pocket between the two inclines said roll is carried with the car and its movement acts as described to stop the motor C.

The slot H¹¹ into which the pin H¹⁰ projects is elongated as shown in Fig. 9 to permit of the starting and stopping movements of the slides K⁸ referred to. From the above description it will be seen that the rolls G are interconnected and positioned so that they not only move together but no two of them are in the path of the cam A⁸ at once; that all of the slides K⁸ are connected so as to move together and so that when the cam A⁸ engages one of the rolls G to raise or lower any one of said slides the motor C will be stopped; that all of the slides H⁹ are connected so as to move together and their notches H⁸ are so positioned as to successively free their latches H⁷, and that the bell cranks F are all connected so as to work together and shift their links F⁴ and F⁷ correspondingly.

Fig. 9 of the drawings shows the selecting, stopping and door-controlling and controlled mechanisms of the first three floors of the building illustrated in Fig. 1. In said Fig. 9, however, the parts are shown in the positions they occupy after the operator at the 1st, 2d, or 4th floor has adjusted the mechanism to stop the car A at the third floor. If the car be at the fourth floor the operator at that point after shifting the handle F into position opposite "3" on the index, as shown at floor 1 of Fig. 9, next throws bell crank H down and motor C is started in a direction to lower car A. The car A then descends until the cam A⁸ engages the roll G at the third floor whereupon the car is stopped and emptied automatically. If the car A is at the first or second floor, then the operator at either of those points throws the bell crank H up and the car A is lifted by the motor C until the cam A⁸ engages the roll G with the results described.

As will be clear from Fig. 9, the car cannot be started in either direction unless all of the doors are closed and when the bell crank F is adjusted to select any one of the floors as the stopping point for the car the door at that floor is automatically unlocked by the bar H⁹ of that floor being moved to bring the notch H⁸ opposite or into the path of the hook of latch H⁷ and at the same time all of the other bars H⁹ are moved so that respective notches H⁸ are carried out of the path of their coöperating latches H⁷.

Having thus described my invention, what I claim and desire to secure by Letters Patent is:

1. In an elevator, a frame provided with guideways, a car movably mounted in said

guideways, means for raising and lowering said car, a series of platforms or stops, selective means located at each platform for predetermining the destination of said car, hand-operated means located at each platform for controlling the starting and direction of movement of said car, means in said car engaging said selective means at predetermined destination or platform for automatically stopping said car, and means for automatically discharging the contents of said car at said destination or platform.

2. In an elevator, a frame provided with guideways, a car movably mounted in said guideways, means for raising and lowering said car, a series of platforms or stops, selective means located at each platform for predetermining the destination of said car, hand-operated means located at each platform for controlling the starting and direction of movement of said car, and means in said car engaging said selective means at predetermined destination or platform for automatically stopping said car and discharging contents.

3. In an elevator, a frame provided with guideways, a car movably mounted in said guideways, means for raising and lowering said car, a series of platforms or stops, selective means located at each platform for predetermining the destination of said car, hand-operated means located at each platform for controlling the starting and direction of movement of said car, means in said car engaging said selective means at predetermined destination or platform for automatically stopping said car, and pivoted means for automatically discharging the contents of said car at said destination or platform.

4. In an elevator, guideways, a car movable in said guideways, means for raising and lowering the car in the guideways, a series of platforms adjacent to the guideways, doors controlling the entrance or exit to or from the platforms and car, selective means at each platform for predetermining the particular platform at which the car is to be stopped, hand-operated means located at each platform controlling the starting and direction of movement of the car, automatic means actuated on the arrival of the car at the designated platform to discharge the contents of the car, and means for automatically locking said hand-operated means in non-operating position if any of the doors are open.

5. In an elevator, guideways, a car movable in said guideways, means for raising and lowering the car in the guideways, a series of platforms adjacent to the guideways, doors controlling the entrance or exit to or from the platforms and car, selective means at each platform for predetermining the particular platform

at which the car is to be stopped, hand-operated means located at each platform controlling the starting and direction of movement of the car, automatic means actuated on the arrival of the car at the designated platform to discharge the contents of the car, means for automatically locking said hand-operated means in non-operating position if any of the doors are open, and means for releasing said locking means when all the doors are closed.

6. In an elevator, guideways, a car movable in said guideways, a series of platforms adjacent to the guideways, doors controlling the entrance or exit to or from the platforms and car, selective means at each platform for predetermining the particular platform at which the car is to be stopped, hand-operated means located at each platform controlling the starting and direction or movement of the car, automatic means actuated on the arrival of the car at the designated platform to discharge the contents of the car, means for automatically locking the hand-operated means in non-operating position if any of the doors are open, means for releasing said locking means when all the doors are closed, and means for automatically locking all doors closed when the car is in motion.

7. In an elevator, guideways, a car movable in said guideways, a series of platforms adjacent to the guideways, doors controlling the entrance or exit to or from the platforms and car, selective means at each platform for predetermining the particular platform at which the car is to be stopped, hand-operated means located at each platform controlling the starting and direction or movement of the car, automatic means actuated on the arrival of the car at the designated platform to discharge the contents of the car, means for automatically locking the hand-operated means in non-operating position if any of the doors are open, means for releasing said locking means when all the doors are closed, means for automatically locking all doors closed when the car is in motion, and means for automatically unlocking the door at the designated platform when the car comes to a stop thereat.

8. In an elevator, guideways, a car movable in said guideways, means for raising and lowering the car in the guideways, a series of platforms adjacent to the guideways, doors controlling the entrance or exit to or from the platforms and car, selective means at each platform for predetermining the particular platform at which the car is

to be stopped, hand-operated means located at each platform controlling the starting and direction of movement of the car, means actuated on the arrival of the car at the designated platform to discharge the contents of the car, and means for automatically locking said hand-operated means in non-operating position if any of the doors are open.

9. In an elevator, a frame provided with guideways, a car movably mounted in said guideways, means for raising and lowering said car, a series of stations, selective means located at each station for predetermining the destination of said car, means located at each station for controlling the starting and direction of movement of said car, and means in said car engaging said selective means at the predetermined destination or station for automatically stopping said car and discharging its contents.

10. In an elevator, a frame provided with guideways, a car movably mounted in said guideways, means for raising and lowering said car, a series of stations, selective means located at each station for predetermining the destination of said car, means located at each station for controlling the starting and direction of movement of said car, means in said car engaging said selective means at the predetermined destination or station for automatically stopping said car and co-acting means to unload said car.

11. In an elevator, guideways, a car movable in said guideways, means for raising and lowering the car in the guideways, a series of stations adjacent to the guideways, doors controlling the entrance to or exit from said car at said stations, adjustable selective means at each station for predetermining the particular station at which the car is to be stopped, means located at each station for controlling the starting and direction of movement of the car, means actuated on the arrival of the car at the designated or predetermined station to discharge the contents of the car, and means for automatically locking said last mentioned means in non-operating position if any of the doors are open.

In testimony whereof, I have signed my name to this specification in the presence of two subscribing witnesses, this 14th day of July, A. D. 1909.

JAMES T. COWLEY.
